UNITED STATES PATENT OFFICE.

WALTER N. VANCE, OF CHICAGO HEIGHTS, ILLINOIS, ASSIGNOR TO DURAND STEEL LOCKER COMPANY, OF CHICAGO, ILLINOIS, A CORPORATION OF ILLINOIS.

LOCKER.

Application filed August 20, 1919. Serial No. 318,692.

To all whom it may concern:

Be it known that I, WALTER N. VANCE, a citizen of the United States, residing in Chicago Heights, in the county of Cook and State of Illinois, have invented a new and useful Improvement in Lockers, of which the following is a specification.

This invention relates in general to lockers and has more particular reference to sheet metal lockers wherein the door is hinged at one side of a door frame and is adapted to close over against and lock to the opposite side.

A principal object of the invention is the provision of a locker of new and improved construction wherein the door may be latched to a single side of the frame and this without danger of the door frame and door springing apart when in latched position or being readily forced apart by unauthorized persons attempting to open the locker.

Another important object of the invention is the provision of a locker wherein the door when closed and latched will have the parts positively and tightly held in interengagement with each other thereby preventing rattling of the parts and adding greatly to their strength in resisting forcing the latching device in attempting to open the locker.

Another important object of the invention is the provision of a sheet metal locker having a door operating and latching mechanism, the parts of which may be easily assembled and thereafter readily removed for replacement or repairs should the necessity arise and this without requiring the shearing of rivets or the deformation or destruction of any of the parts.

Another object of the invention is the provision of a locker requiring the formation of relatively few parts in the provision of the latching device.

Another important object of the invention is the provision of a locker which may be made of relatively light material and have all of the strength and rigidity of construction required.

Another object of the invention is the provision of a locker possessing these and other advantages, which will be cheap to construct and of pleasing appearance and without complicated parts likely to require frequent repair or replacement.

Numerous other objects and advantages of the invention will be apparent as it is better understood from the following description when considered in connection with the accompanying drawing illustrating a preferred embodiment thereof.

On the drawing,

Figure 1 is a partial front elevation of a locker embodying my present invention;

Fig. 2 is a partial vertical view showing the rear of the latching connection disclosed in Fig. 1;

Fig. 3 is a section taken substantially on the line 3—3 of Fig. 1;

Figs. 4 and 5 are enlarged sections taken respectively on the lines 4—4 and 5—5 of Fig. 3;

Fig. 6 is a perspective detail view of the keeper for the manipulating device; and

Fig. 7 is a section taken substantially on the line 7—7 of Fig. 3.

For the purpose of illustrating my invention I have shown on the drawing a locker comprising a door frame 11 in which a door 12 is hinged along an edge as indicated at 13. This door is provided at the hinged edge with a flange 14 extending inwardly and then over and behind the door frame. At its top and bottom it is provided with projecting flanges 15 for engaging the top and bottom of said door frame. At its free edge, i. e. the edge swinging to and from the door frame, the door is provided with an inwardly extending flange 16. Slots are made at intervals along the length of the door to set off parts 17 and when the flange is bent as on the line 18 these parts are left protruding and engage the door frame when the door is closed to act as stops. The provision of these parts 17 leaves recesses or openings 19 through the flange 16 and through these openings are arranged latching lugs 21 adapted to engage back of the door frame as will be presently described to lock the door in closed position. The lugs 21 are formed by slitting and bending out proper portions of a latch bar or strap 22 arranged parallel to and just back of the flange 16.

The latch bar is manipulated by a manipulating device or handle 23 disposed on the outside of the door and having a lug 24 entering through a slot in the door and bolted or otherwise secured at 25 to the latch bar, the other end of the manipulating

device being provided with a tail 26 which is disposed within a keeper 27. This keeper is formed of a strap of material having end lugs 28 disposed through a slot in the door 5 and bent as indicated in Fig. 6. Between the end lugs 28 at each side the material of the body keeper is bulged outwardly at 29 to engage on the outside of the door and co-operate with the bent lugs 28 to lock the keeper 10 in place. Both the keeper and tail 26 of the manipulating device are perforated as indicated at 31 to receive a padlock (not shown in the drawings). The latching bar is moved vertically by operation of the manipulating device to bring it into latched and unlatched position.

The latching lugs 21 are adapted, when the latch bar is elevated, to pass through recesses 32 and 33 provided in the edge of the 20 door frame against which the door closes. As will be readily understood to latch the door it is only necessary to lift the latch bar and close the doors passing the lugs through the recesses and disposing them behind the door frame by lowering the latch bar until the lugs have passed beneath the recesses. The recesses 32 may have any preferred form so far as the mere co-operation 30 with the latch lugs 21 is concerned. I use one or more of these recesses, however, as parts of a dovetail connection to be presently described, these recesses being indicated at 33. Upon the door is provided a lug or projection 34 formed on the end of a member 35 riveted at 36 to the door. The member 35 extends through the centermost recess 19 and lies flat against this part 11 and also against a part 37 which is pressed up therebehind. When the door closes the 40 latching lug 21 passes first through the recess 33 and then may be lowered down to locked position. As the door arrives at completely closed position the dovetailed shoulder 34 enters into recess 33, which being of dovetail form provides shoulders to be engaged by the shoulders 21 to prevent 45 springing of the door frame away from the door. Of course this arrangement may be provided at any point intermediate the ends.

The flange 16 is provided at intervals with 55 depressions 38 and with depressions 39 which form elongated ribs for strengthening the parts of the door flange which are weakened by the opening and said depressions 38 and 39 acting to retain the latch bar away from too great frictional contact with the flange and a similar arrangement is provided at 41 beneath the tail of the manipulating device. The ends of the latch bar are rigidly held in position by inwardly extending 60 depressions 42 back of such projections 17 as are not located adjacent dovetailed projections as 34. A second depression 43 is also provided at the same location to

space the latch bar from too close contact with the inner face of the door and to aid in steadyng it. It will be noted that the outer edges 44 of the parts 17 which are cut out of flange 16 are inclined slightly leaving like 70 inclinations at the edges 45 of the recesses through which the locking lugs or projections extend. This inclination draws the lugs closely against the side of the frame and wedges them tightly in place upon arriving at latched position.

The tail of the rivet 36 is disposed close against the inner face of the latch bar and acts at this point in the manner of the depressions 42. The latch bar is thus held firmly in desired position by the depressions 43 against movement toward and from the flange 16 by the ribs 39, depressions 42 and tail 46 of rivet 36. It is also held tightly in position by the wedging action in the opening in the flange through which it passes, all of which parts tend to reinforce the construction and permit the use of lighter material without sacrifice of rigidity.

It will be manifest that the handle may be disconnected from the latch bar and the latch bar then lifted out of position. This permits of the replacement or repair of any of the latching parts without the shearing of rivets or the deformation or destruction 95 of any of the parts of the door or other latching device.

It is thought that the invention and many of its attendant advantages will be understood from the foregoing description, and it 100 will be apparent that various changes may be made in the form, construction and arrangement of the parts without departing from the spirit and scope of the invention or sacrificing all of its material advantages, 105 the form hereinbefore described being merely a preferred embodiment thereof.

I claim:

1. A locker, comprising in combination a door frame having a recess intermediate its ends, a slideable latching bar carried by the door and formed with set off lugs movable first through said recess and then into locking position, and fixed means carried by the door for engaging in said recess to prevent 115 separation of the door and frame.

2. A locker, comprising in combination a door frame having a shoulder providing recesses in the side against which a door closes, a door mounted in said door frame and having a slideable latching bar formed with setoff lugs passing through said recess and then into locking position, and a fixed shoulder providing projection carried by the door and for engaging in said recess to 120 prevent separation of the frame and door when locked.

3. A locker comprising a door frame, a door hinged therein and closing thereagainst, a latching bar carried by the door 130

and consisting of a metal strip cut and bent to provide set off lugs for engaging the door frame.

4. A locker comprising a door frame, a door hinged therein and closing thereagainst, and having an inwardly extending flange at its side, a metal strip latch bar 75
slidable in parallelism with the flange, and cut and bent to provide a plurality of outwardly set off lugs for engaging the door frame.

5. A locker comprising in combination a door frame, a door hinged therein and closing thereagainst, and having an inwardly extending perforated flange, a sheet metal latching strip located behind the flange and having lugs extending through the perforations for engagement with the door frame.

20 6. A locker comprising a door frame, a door closing thereagainst, a sheet metal latching strip arranged at right angles to the plane of the door and having latching integral elements extending at right angles 80
25 with respect to said strip.

7. A locker comprising a door frame, a door adapted to close thereagainst, a latch strip carried by said door and engaging said door frame, a side of said latch strip being cut into and the material thus separated 85
30 bent to provide latching lugs.

8. A locker comprising a door frame, a door hinged therein and having its free edge turned to form a flange extending into the frame when the door is closed, and projections forming continuations of the body and providing recesses therebehind to facilitate latching the door.

40 9. A locker, comprising in combination a door frame, a door hinged therein and having its free edge turned to form a flange extending within the frame when the door is closed, and projections forming continuations of the body of the door for closing 90
45 against the frame at the free edge.

10. A locker, comprising in combination a door frame, a door hinged therein and having an inwardly extending flange at its free edge, said flange having openings therethrough, a latching device extending through said openings and engaging said door frame, the edges of the material about said opening serving to hold said latching device tightly against said door frame.

11. A locker, comprising in combination a door frame, a door hinged therein and having an inwardly extending flange at its free edge, said flange having openings therethrough, a latching device extending through said openings and engaging said door frame, the edges of the material about said opening being inclined to wedge said latching device against said door frame.

12. A locker, comprising in combination 130
65 a door frame having a recess at its side for

permitting a latching device to pass therethrough, a door carrying a latching device located appropriately with respect to said recess, the body of the door being inwardly flanged and the flanged portion thereof being cut away to provide a recess through which a part of said latching device may extend and to form an integral body part; extending past said recess to cover the same when the door is closed.

13. A locker, comprising in combination a door frame, a door hinged in said frame, said door being constructed of sheet metal and having a portion set off by a slit adjacent its free edge, the material of the edge being bent to form an inwardly extending flange to enter within the door frame, and leaving the portion set off extending to form a stop for engaging the door frame.

14. A locker, comprising in combination a door frame, a door hinged therein and having a flange provided with an opening at its free edge, a latching device disposed behind said flange with the latching part extending through said opening, the material of the body of the door being depressed behind said latching device to aid in confining it closely adjacent said flange.

15. A locker, comprising in combination a door frame, a door hinged therein and having a flange provided with an opening at its free edge, a latching device disposed behind said flange with the latching part extending through said opening, the material of the body of the door being depressed to space said latching device inwardly from the body of the door.

16. A locker, comprising in combination a door frame, a door hinged therein and having a flange provided with an opening at its free edge, a latching device disposed behind said flange with the latching part extending through said opening, the material of the body of the door being given a plurality of depressions, one for spacing the latching device from the body of the door and the other for retaining it closely adjacent said flange.

17. A locker, comprising in combination a door frame, a door hinged therein, a latching device carried by said door frame, the material of the door being depressed inwardly opposite said latching device to space the same from the body of the door.

18. A locker, comprising a door frame, a door hinged therein, a latching device carried by the door, the material of the door being depressed inwardly behind said latching device to aid in retaining said latching device adjacent said door frame when said latching device is in proper position.

19. A locker, comprising a door frame, a door hinged therein and having an inwardly extending flange at its free edge, a latching device slidable behind said flange and hav-

ing a latching device extending therethrough, the material of the body of the door and the material of the flange being depressed to retain said latching device in proper position.

20. A locker, comprising in combination a door frame, a door having an inwardly extending flange, a latching device movable

behind the same and having a latching part, the material of the flange being depressed to provide an elongated narrow projection for engagement by the latching device to prevent extended frictional contact between the flange and latching device. 10

WALTER N. VANCE.
